[57] CLAIM

The ornamental design for a truck cap mounting clamp, as shown and described.

DESCRIPTION

FIG. 1 is a top, front and left side perspective view of a truck cap mounting clamp showing my new design;

FIG. 2 is a left side elevational view;

FIG. 3 is a front elevational view;

FIG. 4 is a rear elevational view;

FIG. 5 is a bottom plan view;

FIG. 6 is a top plan view;

FIG. 7 is a top, front and left-side perspective view of a second embodiment of my new design of FIGS. 1-6;

FIG. 8 is a left side elevational view of FIG. 7;

FIG. 9 is a front elevational view of FIG. 7;

FIG. 10 is a rear elevational view of FIG. 7;

FIG. 11 is a bottom plan view of FIG. 7; and,

FIG. 12 is a top plan view FIG. 7 thereof.
